FRITZ RUDOLPH FRIEDRICH, OF NEW YORK, N. Y.

TYPEWRITER CONSTRUCTION.

Application filed April 24, 1924. Serial No. 703,669.

This invention relates to typewriter construction.

One of the objects of this invention is to provide a typewriter of simple, practical and durable construction and of reliable action. Another object is to provide a typewriter construction that will be of light weight and compact so as to be conveniently portable and yet to be inclusive of dependability of action and durability of construction. Another object is to provide a simple and effective yielding type action and moreover one that will be of flexibility of construction and action and arrangement as to insure proper operation. Another object is to provide a typewriter construction of the above nature that will lend itself readily not only to inexpensive manufacture, but also to production on a large quantity scale. Other objects will be in part obvious or in part pointed out hereinafter.

The invention accordingly consists in the features of construction, combinations of elements and arrangement of parts all of which will be exemplified in the construction hereinafter described and the scope of the application of which will be indicated in the following claims.

In the accompanying drawings, in which there are illustrated several of various possible embodiments of this invention;

Figure 1 is a plan view of an assembled typewriter certain parts being broken away in order to show more clearly certain features of construction;

Figure 2 is a vertical sectional view taken on the line 2—2 of Figure 1;

Figure 2^a is a partial view of the assembled typeheads in retracted position, more particularly as seen along the line 2^a—2^a of Figure 2;

Figure 3 is a fragmentary perspective view of the supporting frame work for the type bars, certain parts being either broken away or omitted in order to show more clearly certain features of the construction;

Figure 4 is a fragmentary sectional view taken along the line 4—4 of Figure 2;

Figure 5 is a fragmentary front elevation of certain parts of the type bar actuating mechanism, and more particularly is a front view as seen substantially along the line 5—5 of Figure 2;

Figure 6 is a vertical sectional view on a smaller scale, showing a preferred embodiment of certain of the features of this invention, and

Figure 7 is a view similar to that shown in Figure 6, but illustrating the preferred embodiment of one of the features of this invention associated with another type of type bar actuating mechanism.

Similar reference characters refer to similar parts throughout the several views of the drawing.

Referring now to the drawings and more particularly to Figures 1 and 2, there is generally indicated at 10 a main supporting frame which is preferably made up out of sheet metal so as to provide a bottom or base member 10^a, vertically extending side walls 10^b, and a vertically extending front wall 10^c. The frame member 10 may be given this form as by stamping, for example. At the right hand end of the main frame member 10 and as viewed in Figures 1 and 2, there extends transversely of the frame member 10 and between the opposite side walls 10^b, a vertical extending sheet metal supporting member 11, preferably secured to the frame member 10 as by riveting or in any other suitable manner. The supporting member 11 is provided with a series of vertically extending slots 11^a through each of which is adapted to pass a key lever 12, the extreme end of which is pivoted upon a fulcrum bar 11^b suitably mounted on the right hand face of the supporting member 11 as by means of the brackets 11^c, for example. The key levers 12 (see Figure 1) are thus not only pivoted at their one end upon a common fulcrum bar 11^b, but also held in spaced relation with respect to one another at their pivoting ends by the vertically extending slots in the supporting member 11.

The key levers 12 extend toward the front part of the apparatus or to the left as viewed in Figures 1 and 2 and are preferably shaped substantially as shown in Figure 2, it being noted that they are depressed intermediate their extreme ends so as to provide sufficient space over them for the accommodation of the mechanism actuated thereby. The key levers 12 are also bent at an intermediate portion, as at the generally indicated portion 12^a in Figure 1 to a progressively greater extent as the extreme outside key levers are approached in passing thereto from the center key lever. The key levers, in extending to the left, pass through the front wall 11^c

10° of the main frame member 10, the front wall 10° being provided with vertically extending space slots, one for each key lever. The key levers, it will thus be seen, are thus 5 compactly arranged and mounted and moreover are well supported and guided for oscillation about the pivoting or fulcruming bar 11^b. Each lever 12 is provided in the usual manner with a vertically extending finger piece 12^b, for example, for manual actuation. A spring 12^c connects each key lever to a stationary part of the apparatus as for example, to the upper end portion of the front wall 10° of frame member 10, in order 10 to hold each key lever with its associated finger piece in normal position and ready for manual actuation. A key lever rest 14 extending across the front wall 10° and provided with a cushion member 14^c upon its 15 lower face, acts to limit the upward movement of the key levers in response to the springs 12^c, and the pad 14^c serves to cushion the return stroke so as to eliminate vibration.

The guiding and supporting members 11 and 10° with which the key levers 12 coact are, as above noted, preferably made of sheet metal and may thus conveniently and inexpensively be given the desired conformation and may also be slotted for the reception 20 of the key levers 12, as by stamping and punching operations respectively.

The supporting member 11 supports the forward end of an auxiliary frame member with which are associated the type bars and 25 actuating mechanisms therefor. This auxiliary frame member is generally indicated at 15 and is preferably made of sheet metal and so shaped as to provide a base or bottom member 15^a and two oppositely disposed and 30 vertically extending side wall members 15^b and 15^c (see more particularly Figure 3). The auxiliary frame member 15, and hence the bottom member 15^a thereof has in general the shape of a sector, the side wall members 15^b and 15^c being thus made to include an 35 angle, the vertex of which is the printing point on the platen 16 (see Figures 1 and 3). Between the side walls 15^b and 15^c are disposed the type bars in such manner that each 40 bar occupies the position of and is movable along the radius of a circle, the center of which is the printing point on the platen 16. The left hand (or front) portions of the auxiliary frame member 15 or type action 45 assembly is supported directly from the bottom member 10^a of the main frame 10 as by means of the downwardly extended legs 15^a and 15^b integrally formed with the side wall members 15^b and 15^c (see more particularly 50 Figure 3). The auxiliary frame member 15, it will thus be seen, thus provides in effect a three-point suspension for the type assembled type bar actuating mechanism, thus greatly facilitating not only the construction, 55 but also the assembly of the apparatus.

At this point it may be noted that the platen 16 may be actuated in the direction of its axis and shiftable vertically for upper case and lower case printing in any suitable manner; the mechanism for actuating the 70 platen is not herein illustrated or described inasmuch as such mechanism forms no part of this invention and may be of any one of various well-known kinds.

As will be seen in Figure 2 of the drawings, the bottom portion 15^a of the auxiliary frame member 15 slopes downwardly toward the left (or the front) of the machine and it will also be seen that the formation given the key levers 12 as hereinbefore noted, permits such downward sloping of the auxiliary frame member to take place, thus insuring compactness of construction and also resulting in a decreased over-all height of the machine. Supported upon the bottom 80 member 15^a and extending between the side wall members 15^b and 15^c, are two vertically extending sheet metal members 17 and 18 spaced from one another in what may be termed a radial direction and each preferably of arcuate shape. The member 17 is provided with a series of vertically extending, but laterally spaced slots 17^a (see Figure 3), these slots 17^a being conveniently punched in the sheet metal member 17 to 90 form in effect a guiding comb. The lower portion of the sheet metal member 18 is also provided with a like series of vertically extending and laterally spaced slots 18^a which likewise are conveniently punched or otherwise formed in the sheet metal member 18. The slots 17^a and 18^a are adapted to slidably support therein the lower bank of type bars 19, which bank includes a number of type bars substantially equal to one-half the 100 number of key levers 12. Each type bar 19 of the lower bank supports at its right hand end a type head 20 upon the right hand face of which are formed the upper case type indicated diagrammatically at 20^a and the 110 lower case type indicated diagrammatically at 20^b, the two types being vertically spaced in the usual manner. Each type bar 19 is extended toward the left (or forwardly) as seen in Figure 2, to provide an end portion 115 19^a adapted first to abut against the type bar rest 21 suitably secured to the bottom member of 15^a and extending transversely thereof (see Figure 3) and second, to provide a guiding portion for coaction with the slot 120 17^a in the guide comb 17 during the printing movement in the direction of a radius of the type bar 19 itself. The type bar rest 21 is provided with a cushioning member 21^a to absorb the shock of the return movement 125 of the type bar 19.

The type bar 19, guided by the radially aligned slots 17^a and 18^a in the guide combs 17 and 18 respectively, is adapted when moved toward the right, as viewed in Fig- 130

ure 2, to strike the lower case type 20^b (or the upper case type 20^a when the platen is vertically shifted) against the platen 16 to effect a printing operation. At the extreme 5 right hand end of the bottom member 15^a of the auxiliary frame 15 there is mounted a type guide generally indicated at 22 and provided with an aperture 22^a through which the type head 20 of a type bar 19 is 10 guided to the printing point on the platen 16. The type guide 22 (see Figure 1) is provided with two side walls 22^b and 22^c aligned substantially with the side walls 15^b and 15^c in order that any one of the type 15 bars 19 may have its respective type head 20 properly guided through the aperture 22^a and to the printing point on the platen 16.

Each type bar 19 of the lower bank is actuated from one of the key levers 12 by 20 linkages of which only one needs to be specifically described. Extending transversely of the auxiliary frame member 15 and preferably secured at its respective ends to the side walls 15^b and 15^c (see Figures 1, 2 and 25 3) is a guide comb 23 of sheet metal construction and of arcuate form, so as to be concentric with the arcuate guide combs 17 and 18, and provided with vertically extending and laterally spaced guiding slots 23^a 30 in number, one for each pair of aligned slots 17^a and 18^a. Within each slot 23^a extends for oscillating actuation about a common fulcrum bar 24 a bell crank lever 25 the lower arm of which is connected as by the linkage 26 to one of the key levers 12 and at the radially aligned portion 12^a thereof (see Figure 1). The upper end of the bell 35 crank lever 25 is connected by a U-shaped link 27, to the type bar 19 and preferably at a point intermediate of the guide combs 17 and 18. A manual depression of a key lever associated with a type bar of the lower bank results in a clockwise swinging of the bell crank lever 25 about the fulcrum bar 24, the resultant substantially linear movement 40 of the upper end of the lever 25 being communicated through the link 27 to the type bar 19. The latter is thus moved in the direction of a radius to bring the type head 20 through the guide 22 and to the printing position. The U-shaped link 27, it is to be noted, inherently by its construction is yieldable in that the width of the U which it forms may readily vary within slight but 45 appreciable limits. The impression compact of the type head with the platen 16 is thus a yieldable or resilient one, it being noted that the long arm of the lever 25 forms with the link 27 a toggle. As the toggle straightens out to carry the type head 20 into printing position, the force with which the type head is carried against the platen increases as is characteristic of the toggle action, and hence the yieldability of the 50 link 27 is effective to take up the reaction of

the increasing printing contact of the type head 20 with the platen 16.

The return movement of the type bar 19 is effected by the spring 12^c acting through this same linkage. 70

The upper portion of the sheet metal member 18 is also provided with a series of spaced slots 18^b in order to form a forward guide comb for the type bars of the upper bank. The spaced slots 18^b, however, are not in vertical alignment with the spaced slots 18^a in the lower portion of the member 18, but rather alternate therewith, as is more clearly shown in Figure 4. The upper end of the sheet metal guide member 18 is secured to a top plate 28 sloping upwardly to the left as seen both in Figures 2 and 3 and forming in effect a partial complement to the bottom member 15^a of the auxiliary frame 15. This top plate 28 supports in depending relation therefrom a guide comb 29 provided with spaced slots 29^a in radial alignment with the slots 18^b in the comb 18. In the upper guide comb portion of the member 18 and in the arcuate guide comb 29 are supported the type bars 30 of the upper bank, for radial movement into printing position. At the left hand end of the top plate 28 is secured a transversely extending type bar rest 31, suitably cushioned as at 95 31^a, to limit as well as cushion the return movement of the type bars 30, the latter being conveniently extended to the left as at 30^a. Each type bar 30 carries a type head 40 of preferably similar construction to the type heads 20 on the lower bank of type bars 19. 100

A guide comb 32 (see Figures 2 and 3) is secured to the left hand end of the top plate 28, and is arcuate in shape so as to be concentric with the guide combs 18 and 29. The guide comb 32 is suitably slotted, to support and guide therein about a common fulcrum bar 33 a series of bell crank levers 34, there being one lever 34 for each type bar 30. Each bell crank lever 34 is connected to a corresponding key lever 12 as by the link 35 whereupon a manual depression of the key lever 12 causes a counter clockwise swinging of the bell crank lever 34 to take place. The resultant movement of the lower end of the lever 34 is communicated to its associated type bar 30 by means of the U-shaped link 36 connected to a type bar at a point intermediate of its two guide combs. The U-shaped link 36 forms with the lever 34 a toggle and coacts therewith in a manner substantially identical to that described in connection with the link 27. The return to normal position of the parts 115 as shown in Figure 2 is brought about by the corresponding spring 12^c acting upon its respective key lever 12. 120

At this point it may be noted that the type bars and various linkages, as well as 130

key levers associated therewith are preferably of sheet metal construction and may conveniently be stamped into any desired shape or form. Moreover, it will be noted that the guide combs 23 and 32 effectively guide their respective bell crank levers in their oscillation about the common pivoting bar, so as to avoid the necessity of carefully machined bearing portions for the respective parts.

10 A cover member 37 of suitable conformation and preferably formed of sheet metal is adapted to be fitted over the case-like main frame member 10 to substantially entirely enclose the type action assembly and certain of its associated mechanisms.

15 From the foregoing, certain of the attendant actions during the operation of the mechanism will be readily understood, and in fact, certain of these have already been hereinbefore set forth in detail. It should be noted, however, that the comb guide 18 through which the type bars of both banks extend and move is spaced a substantial distance from the printing point on the platen 16. The type heads 20 (or 40, as the case may be) are thus freely supported when approaching the printing position by a substantial length of type bar projecting through the guide comb 18. The type bars 19 (as well as 30) are preferably of relatively light sheet metal construction so as to be laterally yieldable throughout a slight, but nevertheless material extent. Colliding type heads or ends of the type bars of either bank of type bars, when in movement, thus freely by-pass each other and there is thus avoided the jamming between type bars or type heads of a given bank.

20 As will be seen from Figures 1 and 2 and 2', each type head (20 or 40) is beveled at its lateral side portions so as substantially to gradually merge the greater thickness of the type head into the lesser thickness of its associated type bar. The type heads, in being thus beveled, greatly facilitate the avoidance of jamming the type heads of a given bank, since, for example, a type head returning from printing position and tending to collide with another type head moving into printing position merely and practically brush one another aside, it being noted that the lateral flexibility of the type bars assists this action.

25 As will be seen from both Figures 2^a and 4, and as already hereinabove noted, the type heads together with their respective type bars of the upper bank are alternated with those of the lower bank. By so relating the type heads of the two banks one to another, and by beveling the type heads (as at 20^c and 40^c) of the two banks at their adjacent or contiguous sides (as viewed in both Figures 2 and 2^a), the jamming of a type head 40 of the upper bank of a type head

20 of the lower bank is effectually avoided. Here also the beveled lower ends 40^d of the type heads 40 or the beveled upper ends 20^d of the type heads 20 act to brush their respective type heads aside from one another as the two approach or pass each other in the vertical plane, in much the same manner as hereinabove described in connection with the approaching or passing movement of two or more type heads of either bank in a substantially horizontal plane. Here also the lateral flexibility of the type bars assists in preventing the jamming of the apparatus.

30 In order further to simplify the operative mechanism and also further to reduce the over-all height of the apparatus, I preferably constructed the type bars 30 of the upper bank as shown at 30^b in Figure 6, to which reference may now be made. The type bar 30^b carries at its forward end a type head preferably as hereinbefore described, and is slidably supported in a guide comb 18 at its one end and adjacent its other end in a guide comb 29, each of substantially similar construction at the guide combs 18 and 29 hereinbefore described. The guide comb 29, of the embodiment shown in Figure 6, however, is extended downwardly to a greater extent and has the spaced slots therein formed adjacent its lower end. The type bar 30^b, while of integral construction throughout, embodies a right hand portion 30^a for coaction with the slots 18^a in the comb 18 and a left hand end portion 30^c preferably parallel to the portion 30^a for coaction with the slots in the lower portion of the guide comb 29. An intermediate and substantially vertically extending portion 30^b connects the parts 30^a and 30^c and forms a shoulder indicated generally at 30^d adapted to limit the retractive movement of the type bar to its normal position of rest. The guide comb 29 thus functions also as a type bar rest and has mounted upon it a yieldable member 29^b for absorbing the shock of the return stroke of the type bars.

35 The type head 40 is thus accurately guided throughout its movements and it will be noted that by giving the type bar 30^b the shape above described, the vertical height of the assembled apparatus is materially reduced, thus making the construction more compact, as well as more simple. The portion 30^c of the type bar 30^b has the same characteristic as to lateral flexibility as the right hand end portion of the type bar 30 of Figure 2, to bring about together with the beveled type heads the hereinabove described avoidance of jamming or interlocking of type bars and type heads either of the same bank or of either bank.

40 The lower type bar, referring still to the embodiment shown in Figure 6, is shown at 19^b and has substantially the same charac-

teristics of construction as the type bar 19 of the embodiment shown in Figure 2. The type bar 19^b however is provided with an integrally formed downwardly extending

5 lug 19^c adapted to coact with the guide comb 17, which latter thus functions as a type bar rest. A suitable cushioning member 17^a is mounted upon the guide comb 17 for absorbing the vibrations due to the return to normal of the type bars 19^b. Thus it will be noted that the construction is further simplified and the number of parts minimized.

The operating, or type bar actuating mechanism is substantially similar to that shown in connection with Figure 2, and like parts are similarly indicated in both figures. It may, however, be noted that the U-shaped yieldable link 36 is preferably connected to the type bar 30^b at the lower end 20 of the connecting portion of 30^c thereof.

Certain of the features of this invention have been illustratively set forth and described hereinbefore in connection with a type bar actuating mechanism of the impression type. In Figure 7 I have illustrated certain of these features in connection with a type bar actuating mechanism of the percussion type and it may be noted that each type bar 19^b of the lower bank is operated 25 into printing position from a key lever 12 by means of a link 41 connected to one arm of a bell crank lever 42 pivotally mounted upon the pivoting rod 33. The lower arm of the bell crank lever 42 is connected by a U-shaped link 43 to a point on the type bar 19^b intermediate of the guide combs 17 and 18. Depression of a type bar 12 to which the link 41 is connected results in the counter clockwise swinging of the bell crank lever 42, the substantially linear movement of its 30 lower extreme end being communicated directly to the type bar 19^b through the yieldable U-shaped link 43 the action of which has already been hereinabove described in connection with Figure 2.

The type bars 30^b of the upper bank are operated by a somewhat similar system of linkages which include a short link 44 connecting a key lever 12 to the short arm of 35 a bell crank lever 45. The bell crank levers 45 are pivotally mounted upon pivoting rod 46 associated with a vertically extending guide comb 47 suitably slotted to guide the levers throughout their oscillating movement. The upper end of the bell crank lever 45 is connected through a U-shaped link 48 to the type bar 30^b, to communicate the movement of the upper end of the bell crank lever 45 to the type bar in response to a 40 depression of the key lever 12 to which the link 44 is connected. The action of the U-shaped link 48 as to its yieldable characteristic has already hereinabove been set forth in connection with Figure 2, but it may be 45 briefly noted that both of the U-shaped links

of 48 and 48 of Figure 7 act beneficially in bringing about a printing operation at the printing point by reason of their inherent yielding quality.

It will thus be seen that there has been 70 provided in this invention a typewriter construction in which the several objects hereinbefore noted, as well as many thoroughly practical advantages are successfully achieved. It will be noted that the construction is simple but rugged, and is of a nature that lends itself readily to inexpensive manufacture and production on a large scale. The several parts may be readily and inexpensively formed out of sheet metal for example, and by reason of the inherent features of construction hereinbefore noted, may be readily assembled without requiring a high degree of precision either in their individual machining or in their assembling. 75 Moreover, it may be noted also that the apparatus is exceedingly compact in arrangement and automatically corrective of jamming tendencies when in action.

As various embodiments might be made of the above invention and as various changes might be made in the embodiment above set forth, all without departing from the scope of this invention, it is to be understood that all matter herein described or shown in the 80 accompanying drawings, is to be interpreted as illustrative and not in a limiting sense.

I claim as my invention:

1. In typewriter construction, in combination, a plurality of type bars, means for supporting movably said type bars in two vertically displaced banks and adapted to permit movement of each type bar to a common printing point, the path of movement of the type bars of the upper bank being 90 inclined to the path of movement of the type bars of the lower bank, and a type head at the end of each type bar, each type head on a type bar of one bank having a tapered inclined portion facing toward the type head 95 of a type bar in the other bank, thereby to facilitate by-passing of one type head by the other.

2. In typewriter construction, in combination, a plurality of type bars arranged in 100 two vertically displaced banks, means for guiding the type bars of each bank in substantially intersecting paths to a common printing point, said means being arranged to guide a type bar of one bank toward the common printing point and in a path substantially intersecting the path of movement of a type bar of the other bank, and a type head at the end of each type bar, said type head having a tapered portion adapted to 105 permit the by-passing of the type heads of one bank and another tapered portion adapted to permit a type head of one bank to by-pass a type head of another bank.

3. In typewriter construction, in combina- 110

- tion, a plurality of type bars each inherently flexible in a direction transversely of its length, means movably mounting said type bars to permit movement thereof to a common printing point and in substantially intersecting paths, a plurality of key levers, one for each type bar, for selectively operating said type bars, said flexible type bars permitting one to yield with respect to the other and thereby to permit one to by-pass the other, a connection between each type bar and its corresponding key lever, said connection including a sheet metal link inherently yieldable within its own plane.
15. 4. In typewriter construction, in combination, a plurality of type bars each inherently flexible in a direction transversely of its length, means movably mounting said type bars to permit movement thereof to a common printing point and in substantially intersecting paths, a plurality of key levers, one for each type bar, for selectively operating said type bars, said flexible type bars permitting one to yield with respect to the other and thereby to permit one to by-pass the other, a connection between each type bar and its corresponding key lever, said connection including a sheet metal link substantially U-shaped in its own plane.
20. 5. In typewriter construction, in combination, a plurality of type bars each inherently flexible in a direction transversely of its length, means movably mounting said type bars to permit movement thereof to a common printing point and in substantially intersecting paths, a plurality of key levers, one for each type bar, for selectively operating said type bars, said flexible type bars permitting one to yield with respect to the other and thereby to permit one to by-pass the other, a connection between each type bar and its corresponding key lever, said connection including a sheet metal link substantially coincident with the length of each type bar, and the type bars of one bank having a rearward portion displaced vertically from the forward portion thereof, thereby to reduce the height of said bank.
25. 6. In typewriter construction, in combination, a plurality of type bars arranged in two vertically displaced banks, means for movably supporting and guiding said type bars to permit them to be moved in substantially intersecting paths to a common printing point and each in a direction substantially coincident with the length of each type bar, and the type bars of one bank having a rearward portion displaced vertically from the forward portion thereof, thereby to reduce the height of said bank.
30. 7. In typewriter construction, in combination, a plurality of type bars arranged in two vertically displaced banks, means for movably supporting and guiding said type bars to permit them to be moved in substantially intersecting paths to a common printing point and each in a direction substantially coincident with the length of each type bar, and the type bars of one bank having a rearward portion displaced vertically from the forward portion thereof, thereby to reduce the height of said bank.
35. 8. In typewriter construction, in combination, a plurality of type bars each inherently flexible in a direction transversely of its length, means movably mounting said type bars to permit movement thereof to a common printing point and in substantially intersecting paths, a plurality of key levers, one for each type bar, for selectively operating said type bars, said flexible type bars permitting one to yield with respect to the other and thereby to permit one to by-pass the other, a connection between each type bar and its corresponding key lever, said connection including a sheet metal link member having at least two arms making an angle one with the other and arranged to permit yielding action within its own plane to vary the angle between said two arms.
40. 9. In typewriter construction, in combination, a plurality of type bars arranged in two vertically displaced banks, means for movably supporting and guiding said type bars to permit them to be moved in substantially intersecting paths to a common printing point and each in a direction substantially coincident with the length of each type bar, and the type bars of one bank having a rearward portion displaced vertically from the forward portion thereof, thereby to reduce the height of said bank.

In testimony whereof I have signed my name to this specification this 21st day of April, 1924.

FRITZ RUDOLPH FRIEDRICH.
